UNITED STATES PATENT OFFICE.

WILHELM MAUSS, OF JOHANNESBURG, TRANSVAAL, SOUTH AFRICA.

PLANETARY CENTRIFUGAL SEPARATOR.

1,126,547.

Specification of Letters Patent.

Patented Jan. 26, 1915.

Application filed April 17, 1914. Serial No. 332,529.

To all whom it may concern:

Be it known that I, WILHELM MAUSS, subject of the King of Great Britain, residing at Commercial Exchange Buildings, 5 Johannesburg, Transvaal, Union of South Africa, have invented certain new and useful Improvements in Planetary Centrifugal Separators, of which the following is a specification, reference being had therein to 10 the accompanying drawing.

The present invention has reference to centrifugal separators for separating solid and liquid material; said separators being of the planetary type in which the separating drums are rotated orbitally at high speed to subject the material to centrifugal force for effecting the separation, and are rotated relatively slowly about their own axes to withdraw the settled solid material 20 from the separation zone to permit its discharge.

The invention is illustrated in the accompanying drawings in which—

Figure I is an elevation partly sectioned 25 on the plane C—D Fig. II, and Fig. II is a sectional plan through A—B Fig. I.

The separating drums 1 are carried in a main frame comprising the upper and lower plates 2, 3, the seatings 4 for the drums and 30 the inclosing cylindrical casing 5. Said frame is rotated about the main axis 6 by means of shaft 7. Each drum is mounted in the seating 4 to rotate about its own axis 8 said rotation being effected relatively slowly 35 by any suitable mechanism indicated by 9, 10. The axes 8 are vertical and each drum is provided above and below its cylindrical portion 11 with inclined flanges 12, 13 forming an annular trough the part 14 of which 40 remote from the axis 6, constitutes the separating zone. The pulp or material to be treated is supplied to an annular hopper 15 and thence through pipes 16 to the drums. As the apparatus is revolved about axis 6, 45 said material collects in said zone 14, where its constituents separate under the influence of the centrifugal force.

The separated liquid constituent is suitably passed away for instance over the upper flange 12, and through the aperture 17 in the casing 5. The solid matter settles on the internal surface of the drum, and is withdrawn from the separating zone by the rotation of the drum about its axis 8 as indicated by the arrow.

In apparatus of the kind it is often diffi-

cult to transport the cake of settled solid material from the settlement zone because as the transporting surface of the drum turns more and more parallel with the direction of the centrifugal force, the deposit tends to break and roll up and to slide back into the separation zone. The object of the present invention is to overcome this difficulty and enable the deposit to be carried right to the inner side of the drum before detachment. With this object a retaining shield 18 is fixed to the plates 2, 3 by the pillars 19 and is positioned within the drum to form between itself and the wall of the drum, a closed channel 20 through which the settled solid material is conveyed. Said channel is made of such size as to be substantially filled by the cake so that the latter is prevented from breaking up and rolling back. In order to prevent an undue thickness of deposit from being forced into the channel and setting up excessive friction, the forward edge 21 of the shield is provided with a cutting edge which cuts off 80 surplus thickness of the deposit presented to it.

The shield 18 is carried round substantially to the point of removal of the deposit, which is preferably the part of the drum 85 nearest the main axis 6, and therefore farthest away from the separating zone 14. It is desirable to remove the cake positively at a definite point by means of a plow 22 fixed to the plates 2, 3. The centrifugal force 90 tends to throw the material off the part of the drum near the main axis 6, which is disadvantageous because it induces friction against the shield 18 and also tends to cause the material to break off irregularly upon 95 emerging from the channel 20. Accordingly such throwing off effect is minimized by bringing the drums as closely as possible to the main axis 6. In the construction shown the two drums almost meet at the axis 6. 100

The transportation of the deposit may be assisted by providing the interior surface of the drum with adhesion rings 23 disposed perpendicularly to the axis 8. Said rings are thin and of considerable width transversely to said axis so as to present a large area to make frictional contact with the deposit. They may be perforated as shown to allow liquid to pass away from the spaces between them. The plow 22 is suitably 11 grooved to pass over said rings.

The plowed off solid matter is projected

2
out of the open bottom of the drum and through the aperture 24 in the lower plate 3. An inverted chute 25 may be fitted to shut off the falling material from the separation zone 14. In case of stoppage of the apparatus, material remaining in the drum can flow out through the spaces 26 and 27 and through the aperture 28 in the casing 5.

What I claim and desire to secure by Letters Patent is:—

1. In a centrifugal separator of the planetary type, the combination with each drum of a shield forming with the part of the wall of the drum which moves toward the main axis, a channel through which is conveyed the material deposited on the wall of the drum.
2. In a centrifugal separator of the planetary type a shield forming a channel with the part of the wall of the drum which moves toward the main axle, said shield extending from the separation zone remote from the main axis to the part of the drum close to the main axis.
3. In a centrifugal separator of the planetary type, the combination with each drum of a shield forming a channel with the part of the wall of the drum which moves toward the main axis, and a plow disposed near to

the termination of said channel for detaching deposit from the wall of the drum.

4. In a centrifugal separator of the planetary type the combination of a plurality of drums almost touching the main axis each drum containing a shield forming a channel with the part of the wall of the drum which moves toward the main axis.

5. In a centrifugal separator of the planetary type the combination of a plurality of drums almost touching the main axis each drum containing a shield forming a channel with the part of the wall of the drum which moves toward the main axis, and means within the drum and adjacent to the main axis for detaching deposit from the wall of the drum.

6. In a centrifugal separator of the planetary type, the combination with each drum of adhesion rings disposed circumferentially on its inner surface, and a shield forming with the wall of the drum a passage for conveying deposited material.

In testimony whereof I affix my signature in presence of two witnesses.

WILHELM MAUSS.
